UNITED STATES PATENT OFFICE.

HERMANUS JOHANUS SPOORENDONK, OF NEW YORK, N. Y., ASSIGNOR OF ONE-HALF TO
JAMES JOSEF MORAN, OF NEW YORK, N. Y.

WINDOW-CLEANER.

No. 905,945.

Specification of Letters Patent.

Patented Dec. 8, 1908.

Application filed February 12, 1908. Serial No. 415,537.

To all whom it may concern:

Be it known that I, HERMANUS JOHANUS SPOORENDONK, a citizen of the United States, residing in New York city, in the county and 5 State of New York, have invented a new and useful Improvement in Window-Cleaners, of which the following is a specification.

This invention relates to a device for cleaning the outsides of windows, and while 10 the device can be used upon any window it is especially adapted for use upon the windows of cabs, locomotives, and upon the cab windows carried by the vestibules of motor cars. It is very desirable that the windows 15 upon locomotive cabs and the front windows upon car vestibules be kept free from smoke or fog so that the engineer or motorman can have a clear view of the track ahead of him. At certain seasons of the year this is almost 20 impossible with the present construction of windows unless the window is lowered, which deprives the engineer or motorman of protection during the season of the year when he is most in need of it.

25 By means of the invention hereinafter described the outer face of the window pane can be wiped from within the car and without opening the window.

In the accompanying drawings,—Figure 1 30 is a front elevation showing the device in position. Fig. 2 is a vertical sectional view taken through a window and through my device. Fig. 3 is a horizontal section on the line 3—3 in Fig. 1. Fig. 4 is a detail end 35 view of the wiper. Fig. 5 is a cross section through a drum.

In constructing and applying the invention, I place upon the outer side of the window frame vertical rack bars 1 upon which 40 travel pinions 2 mounted upon a shaft 3, which shaft carries a rubber roller 4, which roller is provided with a series of spirally arranged ribs 5. Between these ribs are fitted wooden strips 6 which tend to strengthen 45 them. The shaft 3 is journaled loosely in plates 7 and said plates are supported by cords 8, which may be of a flexible wire or any other suitable material, and these cords are wound upon spring actuated drums 9, 50 said drums being carried by the car or cab at any suitable point above the window and each is provided with a spring 9^a.

As shown in the drawings the window frame is offset so that it projects slightly in-

wardly and to the plates 7 are connected also 55 cables 10 which pass downwardly through said frame, and if desired the cables 10 may be formed of wire sufficiently rigid to act as guide bars for the shaft 3, the openings in the window frame through which said guide cables 10 pass holding the moving parts of the device into proper relation with the window.

It will also be obvious that when the device is used upon the front windows of either a car or engine cab a rapid forward movement of the car or engine will of itself create an air pressure upon the wiper which will tend to hold it in contact with the window thereby holding the pinions 2 into engagement with their respective rack bars. The 70 lower ends of the guide cables 10 are therefore within the cab and are connected by a suitable handle 11. By pressing downwardly upon the handle the wiper is drawn downwardly over the outer face of the window pane, and when downward pressure is relaxed the cables 8 will be rewound upon the spring actuated drums and the wiper again lifted to its normal position at the top 75 of the window.

While I have shown two drums it will be obvious that one continuous drum will answer the same purpose and be the equivalent of the single drum with the central portion removed.

Thumb bolts 12 working through brackets 13 mounted upon the window frame have their inner ends bearing on end portions of the rack bars 1 and lock them in position by pressing them against the window sash, by 90 loosening said thumb bolts the lock bars can be removed.

Having thus fully described my invention, what I claim as new and desire to secure by Letters Patent is—

1. A device of the kind described comprising rack bars arranged adjacent the sides of and upon the outer face of a window, a rotatable wiper, pinions carried by said wiper engaging the rack bars, spring actuated 100 drums arranged above the window, cables winding upon said drums and supporting the wiper, as and for the purpose set forth.

2. A window wiper comprising a shaft, a rubber roller carried by said shaft and having spirally arranged ribs, wooden strips fitting between said ribs and holding them in position relative to each other, rack bars ar-

ranged adjacent a window, pinions on the shaft engaging said rack bars, spring actuated drums, cables running over said drums, plates suspended from said cables, the shaft 5 above mentioned being loosely journaled in said plates, and means operable from the inner side of the window for drawing said

plates downwardly, as and for the purpose set forth.

HERMANUS JOHANUS SPOORENDONK.
